Att'y.

UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,353,601.

Specification of Letters Patent. Patented Sept. 21, 1920.

Application filed December 27, 1918. Serial No. 268,447.

To all whom it may concern:

Be it known that I, JAMES L. MCQUARRIE, a citizen of the United States, residing at Montclair, in the county of Essex, State of New Jersey, have invented certain new and useful Improvements in Telephone Systems, of which the following is a full, clear, concise, and exact description.

This invention relates to improvements in telephone systems and has particular reference to a substation apparatus for automatic systems.

In the operation of impulse-transmitting devices associated with substation apparatus, a subscriber frequently adjusts his device for the transmission of impulses corresponding to the first digit of a called number before removing the receiver from the switchhook, and immediately upon removal thereof releases the device. This often results in the mutilation of a call, since sufficient time is not allowed for the operation of the primary switch.

An object of the present invention is to avoid the above difficulty by providing a locking device for the impulse sender which will prevent operation thereof until a predetermined time has elapsed after the removal of the receiver.

Another object is the provision of a device of the above character which is simple in construction, easy to manufacture and readily applicable to substation apparatus of known construction.

The inventive idea involved is capable of receiving a variety of mechanical expressions, one of which, for the purpose of illustrating the invention, is shown in the accompanying drawing; but it is to be expressly understood that said drawing is employed merely for the purpose of facilitating the description of the invention as a whole and not to define the limits thereof, reference being had to the appended claims for this purpose.

The figure is a fragmentary vertical longitudinal section through a deskstand apparatus showing the application of the invention thereto.

Although the invention is shown as applied to a deskstand, it will be obvious that, without departing from the spirit or scope of the invention, the same may also be em-

ployed in connection with other types of substation apparatus, such as a wall-set.

55

In the drawing, 1 indicates a base upon which is mounted a variably operable impulse-sending device 2 of any desired construction, and carried by the base is a standard 3. A supporting element 4 is mounted 60 within the standard and adjacent its upper end has pivot thereto a switchhook 5 carrying the receiver 6. A leaf spring 7 is secured to the supporting element 4 intermediate its ends, and has one end engaged 65 with the depending portion 8 of the inner end of said switchhook, whereby the same is swung upwardly about its pivot when the receiver 6 is removed therefrom.

A locking mechanism is provided for the 70 impulse-sending device 2 and preferably consists of an enlargement 9 formed upon the lower side of the dial of said sending device so as to receive the upper end of a locking pin 10 when the sending device is in 75 normal position and the receiver is on the switchhook. This pin is slidable transversely of the sending device and in parallel relation to the axis of the dial thereof, and has its lower end engaged by the bifurcated end of a lever 11 pivoted intermediate 80 its ends at 12 to the lower end of the supporting element 4. A spring 13 has one end connected to the end of lever 11 opposite that engaging locking pin 10 and normally 85 maintains the latter in its locking position.

Means, such as a time-controlled mechanism, is provided for releasing locking pin 10 when a predetermined time has elapsed after the removal of receiver 6 from the 90 switchhook 5, which operation closes the line circuit for the substation apparatus in a manner well known in the art. This mechanism preferably comprises a rod 14 slidable longitudinally of the standard 3 and mounted in upper and lower guides 15 secured to the supporting element 4. The upper end of rod 14 carries a small roller 16 held in engagement with the lower side of switchhook 5 by means of a spring 17 coiled about the 100 rod 14 and interposed between the upper guide 15 and roller 16. Carried by the supporting element 4 intermediate its ends, is a governing device which preferably comprises a bracket 18 supporting a shaft 19 105 which carries a pinion 20 and a vane 21

which, when rotated, offers sufficient resistance to retard the upward movement of rod 14 under the influence of spring 17 when receiver 6 is removed from switchhook 5 in initiating a call. In order that this vane 21 may be rotated, rod 14 has secured thereto a rack 22, the teeth of which engage pinion 20 so that shaft 19 carrying said vane is rotated when rod 14 moves upward. The end 10 of lever 11 to which spring 13 is secured is disposed in the path of a trip pin 23 carried by the lower end of rod 14 so that at the termination of a definite period of time, determined by the governing device, said trip pin 15 will engage said end of the lever and rock the same about the pivot 12, whereby the upper end of pin 10 will be withdrawn from engagement with the enlargement 9 and thus permit the operation of the impulse-sending device. By providing a locking device of this character, it is apparent that a subscriber cannot adjust his sending device to transmit impulses before a definite period of time has elapsed after the removal 20 of receiver 6 from its switchhook, and the possibility of a false setting of switches is therefore materially reduced. Replacing of the receiver upon the switchhook at the termination of the conversation will cause the 25 latter to force rod 14 downwardly toward its normal position against the tension of spring 17 and thus disengage trip pin 23 from lever 11, and spring 13 will return said lever and consequently locking pin 10 to 30 their normal positions, whereupon the calling device will again be locked.

What is claimed is:

1. In an automatic telephone system, a 40 substation apparatus, an impulse-sending device therefor, means normally engaging a portion of said device for preventing operation thereof, a trip movable upon removal of a receiver from its switchhook for releasing said locking means, and means for retarding the movement of said trip whereby a 45 definite period of time will elapse between the removal of said receiver and the release of said locking means.

2. In an automatic telephone system, a 50 substation apparatus, a telephone line connected thereto, means for closing said line upon the initial movement of said switchhook when the receiver of said apparatus is removed therefrom, an impulse-sending device associated with said substation apparatus, and means for preventing operation of said sending device for a predetermined length of time after the removal of said receiver from its switchhook.

60 3. In an automatic telephone system, a substation apparatus, an impulse sending device therefor, means for locking said device, actuating means for said locking means, means engageable with said actuating means

to cause the same to release said locking means, and means for preventing operation of the actuating means until a predetermined period of time has elapsed after the removal of the receiver from its switchhook. 65

4. In an automatic telephone system, a 70 substation apparatus, an impulse sending device therefor, means for locking said device, a lever engageable with said locking means and operable to move the same to an unlocking position, means operable upon removal of a receiver from its switchhook for actuating said lever, and means for retarding the movement of the last named means to prevent actuation of said lever until a 75 definite period of time has elapsed after the removal of said receiver.

5. In an automatic telephone system, a substation apparatus, an impulse sending device therefor, means for locking said device, a lever engageable with said locking means and operable to move the same to an unlocking position, means operable upon removal of a receiver from its switchhook for actuating said lever, means for retarding the movement of the last named means to prevent actuation of said lever until a definite period of time has been elapsed after the removal of said receiver, and means carried by said last named means for rendering said retarding means effective. 90

6. In an automatic telephone system, a substation apparatus, an impulse sending device therefor, means for locking said device, a lever engageable with said locking means and operable to move the same to an 100 unlocking position, a trip device movable upon the removal of a receiver from its switchhook for engaging and actuating said lever, and retarding means for said trip device operable to prevent engagement thereof with said lever until a definite period of time has elapsed after the removal of said receiver. 105

7. In an automatic telephone system, a substation apparatus including a support, 110 an impulse sending device for said apparatus, means for locking said impulse sending device, a lever pivoted to said support and engageable with said locking means for moving the same to an unlocking position, a trip device carried by said support and movable upon the removal of a receiver from the switchhook for actuating said lever, and means also carried by said support and operated through the movement of 115 said trip device for retarding the movement thereof to prevent the same from actuating said lever until a definite period of time has elapsed after the removal of said receiver. 120

In witness whereof I hereunto subscribe 125 my name this 24th day of December A. D., 1918.

JAMES L. McQUARRIE.
